UNITED STATES PATENT OFFICE.

WILLIAM C. OBERWALDER, OF NEW YORK, N. Y.

NOZZLE.

SPECIFICATION forming part of Letters Patent No. 740,900, dated October 6, 1903.

Application filed February 27, 1903. Serial No. 145,309. (No model.)

To all whom it may concern:

Be it known that I, WILLIAM C. OBERWALDER, a citizen of the United States, and a resident of the city of New York, borough of Manhattan, in the county and State of New York, have invented a new and Improved Nozzle, of which the following is a full, clear, and exact description.

This invention relates to an improvement upon the nozzle disclosed in my prior patent, No. 719,849, dated February 3, 1903.

The object of the present invention is principally to provide means for completely shutting off the flow of water through the nozzle, and this I effect by providing an interior bead located inward of the mouth of the nozzle and arranged to be engaged by the conical divider-block when said block is drawn inward, thus closing the nozzle and attaining the end desired.

Various other minor improvements are involved in the present invention, and all will be fully described hereinafter.

This specification is an exact description of one example of my invention, while the claims define the actual scope thereof.

Reference is to be had to the accompanying drawings, forming a part of this specification, in which similar characters of reference indicate corresponding parts in both views.

Figure 1 is a longitudinal section of the invention, and Fig. 2 is an end elevation thereof.

a indicates the nozzle proper, which is provided at its mouth or discharge end with a flaring surface *a*², as in my prior patent. Within the nozzle, just below the mouth thereof, is an annular bead *a*³.

d indicates the divider-block, having, as before, the conical part *d*¹ and the cylindrical part *d*². This divider-block coacts with the flared portion *a*² of the mouth of the nozzle the same as in my prior patent, and by moving the divider-block inward until the base of its conical portion *d*¹ engages the bead *a*³ the nozzle will be completely closed and the passage of water therethrough prevented.

When the divider-block is moved outwardly from this bead *a*³, the operation of the nozzle in forming the varying streams of water is in no way affected by the bead *a*³. It will thus be seen that by means of the present invention I am enabled to obtain the same spray-

ing effect as in the nozzle as previously constructed, and at the same time by simply moving the divider-block to its extreme inward position the nozzle will be entirely closed.

The divider-block is carried by the sleeve *b*, which is threaded on the nozzle *a* and has a cup *b*¹ formed on its outer end, this cup flaring outward, as indicated, and carrying a number (preferably four) flattened arms or knife-edges *c*, these being disposed edgewise to the nozzle and being fastened to the divider-block to hold the same in position. Owing to the peculiar form of the arms *c*, they do not obstruct the stream of water passing from the nozzle. This construction provides a neat and attractive nozzle, and at the same time it protects the relatively slender knife-like arms *c* from destructive blows.

The sleeve *b* may be threaded on the nozzle *a* the same as in my prior patent, or, if desired, a thread may be formed on the nozzle only and one or more pins fastened to the sleeve to work with the threads, as indicated in the present drawings. This latter construction is much cheaper than the former, and the effectiveness is the same.

Various changes in the form, proportions, and minor details of my invention may be resorted to at will without departing from the spirit and scope thereof. Hence I consider myself entitled to all such variations as may lie within the intent of my claims.

Having thus described my invention, I claim as new and desire to secure by Letters Patent—

1. A spraying-nozzle, comprising a nozzle proper, a divider-block, and means for adjustably connecting the two, said divider-block and nozzle proper having surfaces coacting to vary the stream of water passing from the nozzle and the nozzle also having an interior annular bead inward from the said surface of the nozzle proper which coacts with the divider-block, said bead being engaged by the divider-block at the limit of its inward movement completely to close the nozzle.

2. A spraying-nozzle, comprising a nozzle proper having a flaring mouth, a cylindrical interior surface inward of the mouth and an annular interior bead inward of said cylindrical surface, a cylindrical divider-block of less diameter than the said interior cyl-

drical surface of the nozzle proper, the divider-block having a conical inner end and being capable of engaging the interior bead at the inward movement of the divider-block
5 completely to close the nozzle, and means for adjustably connecting the divider-block and the nozzle.

3. A nozzle, comprising a nozzle proper having a cylindrical interior, and an annular interior bead inward of said cylindrical interior, a divider-block of less diameter than the cylindrical interior of the nozzle proper and

capable of engaging said annular bead at the limit of the inward movement of the divider-block, and means for adjustably connecting 15 the nozzle proper and the divider-block.

In testimony whereof I have signed my name to this specification in the presence of two subscribing witnesses.

WILLIAM C. OBERWALDER.
